FIG. 1.

FIG. 2.

INVENTOR.

George Potstada.

BY
Carlo P. Griffin
ATTORNEY.

UNITED STATES PATENT OFFICE.

GEORGE POTSTADA, OF OAKLAND, CALIFORNIA.

ELECTRIC-CORD RETAINER.

1,418,462.

Specification of Letters Patent. Patented June 6, 1922.

Application filed March 31, 1920. Serial No. 370,317.

To all whom it may concern:

Be it known that I, GEORGE POTSTADA, a citizen of the United States, residing at Oakland, in the county of Alameda, State of California, have invented a new and useful Electric-Cord Retainer, of which the following is a specification in such full and clear terms as will enable those skilled in the art to construct and use the same.

10 This invention relates to a retainer for the electric cord of a lamp or other electrical fixtures such as telephones or heaters. An object of the invention is to produce a receptacle for the cord which will conceal it 15 from view, and which will be in some instances part of the base of the lamp.

Other objects of the invention will appear as the description proceeds.

An embodiment of the invention is shown 20 in the accompanying drawings in which the same reference numeral is applied to the same portion throughout, but I am aware that there may be modifications thereof.

Fig. 1 is a side elevation of a heater having this cord retainer applied thereto.

Fig. 2 is a vertical sectional view of a lamp base having this cord retainer applied thereto, and

Fig. 3 is a sectional view through the center of the retainer shown in Fig. 1.

The retainer comprises a tube 1 which is connected to the heater stand 2 by means of the detachable clamp 3. At the end of the tube there is a bell shaped cover 4, which is secured to said tube and slidable on the tube 35 is a similarly shaped bell 5. The bell 5 has two hooks 6 and 7 to enable the user to pull it away from the bell 4, pin 8 and spring 9 within the tube 1 serve to hold the bells 4 40 and 5 normally in contact with each other. The bell 5 will have an opening therein for the cord 10 to pass through and the bell 5 also has a notch 11 cut in its edge for the 45 cord to pass through when the two bells are in contact with each other.

In the form of the invention shown in Fig-

ure 2, the numeral 20 represents a table or other structure to which the lamp base 21 is secured by means of the spring 22. The lamp base has a tube 23 rigidly connected thereto, within which tube there is a spring 24. The spring 24 is connected to the base 21 and at the other end to the tube 25. The tube 25 slides within the tube 23, and is connected to the lamp socket 26. This tube 55 is also connected to the hood 27, which gives the appearance of forming the lamp base, whereas it really forms a receptacle for the cord.

The lamp cord 28 extends from the lamp 60 socket through slots in the tubes 23 and 25, which permit a certain movement of the base hood 27 with respect to the base 21. Normally the spring 24 pulls the hood 27 snugly against the base 21, but when the cord is to 65 be wound on the tube 23, or unwound therefrom, the hood 27 is pulled away from the base 21, slightly. In order to provide a resilient surface for the base to prevent it from injuring polished woodwork when secured thereto, a rubber ring 30 is inserted in the base entirely around the same and a spring ring 31 with sharp points 32 along its length and having sharp points 33 and 34 at its ends are used to secure the rubber 75 ring in place.

What I claim is as follows, but various modifications may be made in the construction shown in the drawings and above particularly described form, within the purview 80 of my invention:

An electric cord receptacle comprising a base, a clamp for securing the base to any suitable object, a tubular post carried by the base, a spring within said tubular post, and 85 a cover connected with said spring, said cover being adapted to conceal an electric cord when wound upon the tubular member under the cover.

In testimony whereof I have hereunto set 90 my hand this 27 day of Feb., A. D. 1920.

GEORGE POTSTADA.
